UNITED STATES PATENT OFFICE.

MARTIN J. SUNDERLIN, OF WATKINS, NEW YORK.

CARBON-HOLDER FOR TYPE-WRITERS.

SPECIFICATION forming part of Letters Patent No. 617,841, dated January 17, 1899.

Application filed May 16, 1898. Serial No. 680,780. (No model.)

To all whom it may concern:

Be it known that I, MARTIN J. SUNDERLIN, a citizen of the United States, and a resident of Watkins, in the county of Schuyler, in the State of New York, have invented new and useful Improvements in Carbon-Holders, of which the following, taken in connection with the accompanying drawings, is a full, clear, and exact description.

10 This invention relates to the carbon-holder shown in my Letters Patent No. 555,748, dated March 3, 1896.

The objects of my present invention are, first, to provide a carbon-holder which shall 15 permit the carbon-sheets to be more readily attached to and removed from the holder, and thus facilitate the operation of removing said sheets when required; secondly, to allow the carbon-sheets to be manipulated more conveniently and without handling the sheet, and, thirdly, to render the carbon-holder more convenient and efficient in its general 20 operation; and to these ends the invention consists in the improved construction herein- 25 after described.

The invention is fully illustrated in the accompanying drawings, in which—

Figure 1 is a plan view of the upper or main portion of the holder in position to receive the carbon-sheets. Fig. 2 shows said holder complete with the carbon-sheet attached thereto. Fig. 3 is a plan view of the upper part of the carbon-holder in condition for being introduced into the type-writing machine. Fig. 4 is a longitudinal section on line X X in Fig. 2. Figs. 5 and 6 are plan views of modifications of the top portion of the holder, and Fig. 7 shows a modification of the attaching-tab of the carbon-sheet.

40 A denotes the type-protecting back sheet, which is usually interposed between the platen and the paper to be written on. Across the upper end of this sheet is pasted a strip b of stiff paper or other suitable material. A portion in the center of this is unpasted and loose from the back sheet and formed with a suitable catch for connecting thereto the carbon sheet or sheets, for which purpose I preferably provide said loose portion of the strip 45 with an inverted-U-shaped slit forming an upward-projecting tongue or hook c for the attachment of the carbon sheet or sheets S, as hereinafter described. At opposite sides of this hook the strip b is widened and has the lower margins thereat loose from the back 55 plate to form downwardly-projecting flaps d d. The lower edge of the fastened portion of the strip b serves as a gage or stop in placing the carbon-sheet S on the holder, in which operation the top edge of said sheet is inserted 60 under the flaps d d and placed against the fast edge of the strip, and this causes the sheet to be adjusted to its requisite position on the back sheet A. To facilitate said adjustment, I provide the fastened portion of 65 the strip b with tongues b' b' for holding the flaps d d in upturned position, as shown in Fig. 1 of the drawings, while placing the carbon-sheet against the aforesaid gage.

For connecting the carbon-sheet S to the 70 holder b I attach to the upper end of said sheet a tab e, provided with a transverse slot e', receiving through it the hook c, as shown in Fig. 3 of the drawings.

To allow the carbon-sheet to be shifted 75 longitudinally, so as to cause the line of writing to come between the previously-worn lines in said sheet, and thus prolong the utility of said sheet, I provide the strip b with an additional inverted-U-shaped slit inside of the 80 primary correspondingly-shaped slit and extending farther toward the lower end of said strip, which additional slit forms a secondary tongue or hook c' for connecting to it the slotted tab e of the carbon-sheet. The same ef- 85 fect, however, may be obtained by providing the tab e with two transverse slots e' e'', as shown in Fig. 7 of the drawings. I do not limit myself to the use of the slotted tab e on the carbon-sheet S, as the connection of said 90 sheet to the holder may be accomplished by various interlocking devices or catches on said parts. One of said modifications consists of lateral projections e³ on the tab e and two tongues or hooks c² c² on the strip b, en- 95 gaging said projections, as represented in Fig. 5 of the drawings. A further modification consists of a hook h formed on the tab e, inserted into a transverse slot h' in a loose portion of the strip b, as shown in Fig. 6 of the 100 drawings. In either case, however, I prefer to attach to the upper end of the back sheet a flap f, which is provided with an eye f', by which to suspend the carbon-holder when not

applied to the type-writing machine. The chief purpose, however, of this flap is to fold over and cover the carbon-sheet attachments, as shown in Fig. 3 of the drawings, and therefore by prevent interference with said attachments during the passage of the carbon-sheet holder through the type-writing machine.

To obviate the necessity of handling the carbon-sheet, I attach to the lower end of said sheet a tab or suitable thumb-piece *i*, by which to manipulate the sheet.

What I claim as my invention is—

1. The combination, with the back sheet and carbon-sheet, of a strip secured across the upper end of said back sheet and formed with a catch, and a tab attached to the carbon-sheet and formed to engage said catch.

2. The combination, with the back sheet and carbon-sheet, of a stiff strip extending across the upper end of said back sheet and fastened thereto, upwardly-projecting hooks formed integral with said strip and a tab attached to the carbon-sheet and perforated to receive through it the aforesaid hook.

3. The combination, with the back sheet and carbon-sheet, of a strip pasted across the upper end of said back sheet and formed with an upwardly-projecting hook in the center of its length and with flaps at opposite sides of said hook, and a tab attached to the carbon-sheet and perforated to receive through it the aforesaid hook as set forth.

4. The combination, with the back sheet and carbon-sheet, of a strip pasted across the upper end of said back sheet and formed with a catch, a tab attached to the carbon-sheet and formed to engage said catch, and a flap attached to the upper end of the back sheet to fold upon and cover the carbon-sheet attachments as set forth.

5. The combination, with the back sheet and carbon-sheet, of a strip pasted across the upper end of said back sheet and formed with an upwardly-projecting hook in the center of

its length and with flaps at opposite sides of said hook, a tab attached to the carbon-sheet and perforated for the reception of said hook, and a flap attached to the upper end of the back sheet to fold upon and cover the aforesaid hook as set forth.

6. The combination with the back sheet and carbon-sheet, of a strip pasted across the upper end of the back sheet to gage the carbon-sheet, and provided with an upward-projecting hook, and a tab attached to the upper end of the carbon-sheet and provided with a slot receiving through it the aforesaid hook as set forth.

7. The combination with the back sheet and carbon-sheet, of a strip pasted across the upper end of the back sheet to gage the carbon-sheet and provided with a plurality of upward-projecting hooks located at different distances from the top edge of the back sheet, and a tab attached to the upper end of the carbon-sheet and provided with a slot for receiving through it either of the aforesaid hooks as set forth.

8. The combination with the back sheet and carbon-sheet, of a strip pasted across the upper end of said back sheet and having a loose central portion provided with an inverted-U-shaped slit forming an upward-projecting hook, flaps projecting downwardly at opposite sides of the aforesaid hook and tongues on the aforesaid strip adapted to hold the downwardly-projecting flaps in upturned position, a flap attached to the upper end of the back sheet and covering the aforesaid hook, a tab attached to the upper end of the carbon-sheet and provided with a slot receiving through it the aforesaid hook, and a tab on the lower end of the carbon-sheet for manipulating the same as set forth.
